ATTORNEY

UNITED STATES PATENT OFFICE.

JOHN B. HOLTZCLAW, OF LOS ANGELES, CALIFORNIA.

DESIGN FOR A PILLAR-SEAT.

No. 39,265.

Specification for Design.

Patented April 14, 1908.

Application filed January 15, 1908. Serial No. 411,026. Term of patent 14 years.

To all whom it may concern:

Be it known that I, JOHN B. HOLTZCLAW, residing in the city of Los Angeles, county of Los Angeles, and State of California, have invented a new, original, and ornamental Design for Pillar-Seats, of which the following is a specification, reference being had to the accompanying drawing, forming part thereof.

The figure is a plan view of a pillar seat, showing my new design.

I claim:

The ornamental design for a pillar seat, as shown.

JOHN B. HOLTZCLAW.
